EDWARD LORD MCLOUD, OF ESPARTO, AND PATRICK KERWIN, OF MANCHESTER, CALIFORNIA.

POWER PIPE TONGS.

Application filed December 7, 1922. Serial No. 605,370.

To all whom it may concern:

Be it known that we, EDWARD L. MCLOUD and PATRICK KERWIN, citizens of the United States, residing at Esparto and Manchester, respectively, in the counties of Yolo and Mendocino, State of California, have invented a new and useful Power Pipe Tongs, of which the following is a specification in such full and clear terms as will enable those skilled in the art to construct and use the same.

This invention relates to a power pipe tongs, and its object is to provide means whereby the engineer or drill-man may operate the tongs at a distance therefrom to either unscrew or screw together two sections of pipe.

One object of the invention is to provide means whereby the tongs may be adjusted to release and engage the pipe with a very small amount of slack motion thereby increasing the operating efficiency of the tongs.

Another object of the invention is to provide a form of latch for connecting the tongs together, which will enable the tongs to be very quickly applied or removed from the pipe, the latch being operated at a distance from the tongs by means of rope or small cable.

Another object of the invention is to provide means whereby the tongs may be used on different sizes of pipe bushings for that purpose being used to increase or diminish the opening between the jaws of the tongs to accommodate different sizes of pipe.

Another object of the invention is to provide means for holding a jaw in the proper position with respect to the other knife edge bearings being used to prevent that jaw from twisting with respect to the second jaw, and also to insure holding the latch tight.

Other objects of the invention will appear as the description proceeds.

An embodiment of the invention is shown in the accompanying drawings in which the same reference numeral is applied to the same portion throughout, but we are aware that there may be modifications thereof.

Fig. 1 is a plan view of the complete tongs ready to be applied to a pipe,

Fig. 2 is a side elevation of the tongs looking from the top of Fig. 1,

Fig. 3 is a perspective view of one of the

bushings used to change the size of the tongs opening, and

Fig. 4 is a perspective view of the latch for connecting the tongs jaws together.

The numeral 1 indicates a lever with a series of holes therein for connecting it to suitable supporting and operating cable. Two of the holes in the lever are provided with pins 2 and 3 which connect said lever to the semicircular tong jaws 4 and 5.

At the opposite side from the pivot points, one of these tong jaws has a notch to receive a knife edge 6 on the tongs jaw 4.

The jaw 5 carries a latch 7 which has a hook 8 to engage a shoulder on the end of the tong jaw 4. This latch also has a handle 9 to which a rope or cable 10 is attached which extends away from the tongs to any suitable place of operation by the drill-man or engineer.

Pins 12 and 13 are connected to the tong jaws for enabling the pipe man to rapidly engage the tong jaws with a fresh length of pipe when necessary. Two links 14 and 15 connect the jaw 5 with the operating lever 1.

The link 15 has a lug 16 thereon which projects into the operating plane of the lever 1, and a set-screw 17 passing through said lug serves to increase and diminish the movement required of the lever 1 to engage or disengage the tong jaws from the pipe. If the set-screw is in the position shown in Fig. 1, the lever 1 will have considerable movement, but if it is screwed out slightly the lever will have very much less movement before it releases the tongs from the pipe on the backward movement.

In order to provide for applying the same tongs to pipe of different sizes, bushings 18 are used which have a lug on the outside thereof to fit into recesses in the jaws 4 and 5.

Screws 19 and 20 serve to hold the bushings in place.

It will be understood by those skilled in the art that such tongs, as are here described, are used in connection with the driller of deep oil or water wells where the pipes will be from 6" to 16" in diameter and the tongs themselves weigh several hundred pounds, so that they must be supported by a cable or rod and must be operated by power.

When the tongs has been engaged with a pipe, the latch is placed in the position

shown in Fig. 1, the spring 22 serving to hold it in that position. The well driller or engineer then operates the engine to either screw up the pipe or to unscrew it as the case may be, and when he gets through with that particular operation, releases the tongs by pulling on the cable 10. At this same time, the tongs will be pulled away from the pipe and other operations will be free to take place without interference from the tongs.

What we claim is as follows, but various modifications may be made in the construction shown in the drawings and above particularly described form, within the purview of our invention.

A power pipe tongs of the class described

comprising an operating handle, a jaw pivotally mounted thereon having a knife bearing at its outer end, a second jaw resting against said knife bearing, a spring latch for holding the two jaws together adjacent said knife bearing, a link connecting the second jaw to the handle to enable the jaws to be tightened upon a pipe to turn it and a lug carried by said link having an adjustable bolt to enable the jaws to be quickly loosened when the handle is turned in the proper direction.

In testimony whereof we have hereunto set our hands.

EDWARD LORD McCLOUD.

PATRICK KERWIN.
